UNITED STATES PATENT OFFICE.

WILLIAM C. JAEGER, OF PHILADELPHIA, PENNSYLVANIA.

DESIGN FOR A GAME-BOARD.

43,846.

Specification for Design.

Patented Apr. 15, 1913.

Application filed August 24, 1912. Serial No. 716,914. Term of patent 14 years.

To all whom it may concern:

Be it known that I, WILLIAM C. JAEGER, a citizen of the United States, residing in the city and county of Philadelphia and State of Pennsylvania, have invented a new, original, and ornamental Design for a Game-Board, of which the following is a specification, reference being had to the accompanying drawing, forming part thereof.

The figure is a plan view of a game board showing my new design.

I claim:—

The ornamental design for a game board as shown.

WILLIAM C. JAEGER.
